INVENTOR

Paul H. E. Scherbner

BY

E. M. Marshall

ATTORNEY

UNITED STATES PATENT OFFICE.

PAUL H. E. SCHERBNER, OF NEW YORK, N. Y.

GRATING.

1,309,698.

Specification of Letters Patent.

Patented July 15, 1919.

Application filed January 29, 1919. Serial No. 273,748.

To all whom it may concern:

Be it known that I, PAUL H. E. SCHERBNER, a citizen of the United States of America, and a resident of New York, county and State of New York, have invented certain new and useful Improvements in Gratings, of which the following is a specification, reference being had to the accompanying drawings, forming a part thereof.

10 My invention relates to gratings and its object is to provide grating of simple and inexpensive construction and which has great strength. More specifically, the object is to improve the manner in making grating by means of which the cost of manufacturing is greatly reduced.

15 In order that my invention may be thoroughly understood I will now proceed to describe the same in the following specification, and will then point out the novel features thereof in the appended claim.

Referring to the drawings:

Figure 1 is a plan view of a portion of a grating made according to and embodying 25 my invention.

Fig. 2 is a sectional elevation of the grating shown in Fig. 1 with some of its parts incompletely finished. The section of this figure is taken on the line 2—2 of Fig. 1.

30 Fig. 3 is a sectional elevation corresponding with Fig. 2 and illustrating one of the steps taken in manufacturing this improved grating.

Fig. 4 is a sectional elevation of the same 35 structure taken on the line 4—4 of Fig. 1, with some of the parts thereof incompletely finished.

Fig. 5 is a sectional elevation corresponding 40 with Fig. 4, illustrating a modified form of construction.

Fig. 6 is a sectional elevation also corresponding with Fig. 4, showing a further modification of construction.

45 Fig. 7 is a sectional elevation corresponding with Fig. 2 illustrating another form of construction which also embodies this invention.

Fig. 8 is a sectional elevation taken at 50 right angles to the section of Fig. 7, showing the form of grating illustrated in the latter figure.

Like characters of reference designate corresponding parts in all the figures.

55 The grating comprises a plurality of flat metallic strips spaced apart, some running in one direction and others at right angles

to the first. For the sake of differentiation I will call those parts which are designated by the reference numeral 10, longitudinal members, and those designated by 20, transverse members. The metal of the longitudinal members is cut away at spaced intervals to form slots 11 terminating short of the edges. The slots are of approximately the same width as the thickness of the members 60 20 but shorter than their vertical dimension. The metal remaining between the upper ends of the slots and the upper edges of the members 10, is designated by 12. Slits 13 are cut downwardly from the edges of the slots, 65 preferably diverging as shown in Fig. 4. The metal between these slits is bent outwardly as at 14, a sufficient amount to make the distance between these parts and the parts 12 slightly greater than the vertical 70 dimension of the members 20.

Notches 21 are cut at spaced intervals in the upper edges of the members 20. These notches are of a width approximately the same as the thickness of the member 10 and 80 of a depth approximately the same as the vertical dimension of the parts 12.

The members 20 are passed through the slots in members 10, as shown in Fig. 3. After this the members 20 are raised into the 85 positions shown in Fig. 2 with the metal at the sides of the notches overlapping the sides of the parts 12. Then the parts 14 are bent back under the lower edges of the members 20, as shown at 15 in Figs. 2 and 3. In this 90 simple manner a grating of great strength is constructed.

The object of diverging the slits 13 is to increase the length of the lines 16 where the metal is bent in order to prevent weakening 95 the metal, by bending it. A similar result may be attained in the way shown in Fig. 5, wherein rectangular parts 17 of the metal at the lower ends of the slots are bent outwardly and back again. If it is not deemed 100 necessary to increase the length of the line of bending, the slits may be made continuations of the sides of the slots as shown in Fig. 6, in which case the parts 18 which are bent outwardly and back again, are of substantially 105 the same width as that of the members 20.

It is within the scope of this invention to use something other than integral parts of the members 10 to maintain the members 20 110 in their raised positions. As an example of another way of accomplishing this result, I

have shown in Figs. 7 and 8 the longitudinal members 10 provided with deeper slots 11^a which permit the insertion of the members 20 without any preliminary bending of the 5 metal. In this case after the members 20 have been inserted and raised, flat rods 25 of about the same width as that of the members 20 and of a height about equal to the depth of the slots 21, are placed in the slots under 10 the members 20. With this construction it may be desirable to prevent lengthwise displacement of the rods 25 and this may be done by upsetting their ends as at 26, or by bending their ends over the outer of the 15 members 10 as shown at 27.

I have illustrated and described several forms of construction in order to show that I do not limit myself to any specific form or construction and I intend no limitations 20 other than those imposed by the appended claim.

What I claim is:

Grating comprising a plurality of longitudinal members cut away at spaced intervals to form slots terminating short of their edges and with slits from the edges of the slots terminating below the slots at distances apart greater than the width of the slots, a plurality of narrower transverse members passing through said slots and provided 25 with spaced notches in their upper edges, the parts of the longitudinal members between the slits therein being bent up under the transverse members to maintain the transverse members in positions with the parts 30 thereof adjacent the notches overlapping the longitudinal members at the upper ends of the slots therein.

In witness whereof, I have hereunto set my hand this 24 day of January, 1919.

PAUL H. E. SCHERBNER.
